UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

BOBBIN-TIP SUPPORT FOR FILLING REPLENISHING LOOMS.

Application filed March 26, 1926. Serial No. 97,575.

This invention relates to filling replenishing looms and more particularly to bobbin tip supports for controlling the tip end of filling carriers or bobbins during the transfer of the filling carriers or bobbins from the hopper or magazine to the shuttle.

It is now the common practice to provide filling replenishing looms with transferring mechanism associated with means for directing the tip end portion of the bobbin into the shuttle. In some cases the bobbin tip support is pivotally mounted on a fixed arm extending rearwardly from the trans-
ferrer stud, with the end of the tip support
normally extending below and in the path
of the tip of the bobbin, and when replen-
ishment is effected the bobbin tip support
turns upon its pivot to permit the tip end of
the bobbin to pass into the shuttle. In other
cases it has been proposed to associate with
the transerrer itself a tip holder which will
grasp the tip end portion of the bobbin and
hold it positively during the movement of
the transerrer in effecting replenishment of
filling. Each of these mechanisms has served
satisfactorily in many cases.

One of the objects of the present invention, therefore, is to provide a bobbin tip support which is simple in construction and
wherein the bobbin tip support as well as the
arm which supports the bobbin tip support
shall be pivotally mounted for movement by
the transerrer during replenishment of
filling.

In accordance with the present invention, the bobbin tip support is pivotally mounted upon the bobbin tip supporting arm which is itself pivotally supported, and the pivotally mounted bobbin tip support is normally
out of the path of movement of the tip of the
filling carrier and is caused to move into
the path of movement below the tip of the
filling carrier by the downward action of
the transerrer.

The invention and new combination of
parts will best be made clear from the fol-
lowing description and the accompanying
drawings of one good form thereof.

In the drawings:—

Fig. 1 is a sectional side elevation of por-
tions of a filling replenishing loom, having
the present invention associated therewith,
and showing the parts in their normal posi-
tion during loom operation;

Fig. 2 is a view similar to that of Fig. 1
but showing the relation assumed by the
parts when the transerrer moves down-
wardly to transfer a filling carrier to the
shuttle;

Fig. 3 is a view similar to that of Fig. 2
showing the relation of the parts when the
filling carrier has been finally moved into
the shuttle by the transerrer;

Fig. 4 is an enlarged perspective view
showing the transferring mechanism with
the present invention associated therewith;
and

Fig. 5 is an enlarged detail partly in sec-
tion of the bobbin tip support.

Mounted upon the loom frame 1 at the
filling replenishing side of the loom is the
magazine or hopper 2 in which are mounted
the filling carriers or bobbins 3. In the
present instance, the filling carrier or bob-
bin, which is in transferring position as in-
dicated at the left lower series of filling car-
riers in Fig. 1, normally rests against a
guide or abutment 4, and is normally above
the throat or passageway 5 leading to the
shuttle beneath.

The lay 6 has the usual shuttle box at the
replenishing side, and the shuttle 7 is pro-
vided with the bottom opening 8 for the
ejection of the spent filling carrier on re-
plenishment of filling. These parts may all
be of usual construction.

Pivotally mounted upon the stud or dead
shaft 9 supported by the loom frame, is the
transerrer 10, having a head portion 11 for
engagement with the filling carrier or bob-
bin during transfer. The downwardly ex-
tending arm 12 which is connected to the
transerrer 10 has pivotally connected thereto
at 13 a dog 14 which is adapted to be en-
gaged by a bunter 15 on the lay to effect re-
plenishment of filling. A spring 16 nor-
mally acts upon the transerrer 10 to main-
tain it in its upward inactive position, and
upon call for replenishment by any suitable
form of indicating means, the dog 14 is
moved into the path of the bunter 15 and
the transerrer is thereby given its transfer
movement. The parts so far described are
of usual construction and as usual, also, the
hopper 2 is provided with means for effect-
ing its rotative movement to bring a fresh
filling carrier into position for transfer. In
the present instance, the rotating means

consists of the rack teeth 17 secured to the hopper which may be engaged and actuated step-by-step as usual by the actuating pawl 18. Since this mechanism, however, forms no essential part of the present invention, it is not necessary to further describe it.

The transfer 10 has extending laterally therefrom the tip pusher arm or rod 19, the outer extremity of which may be down-turned, as indicated in Fig. 4, and provided with a notched portion 20 to engage the tip end of the bobbin to be transferred.

Secured upon the dead shaft or stud 9 is a sleeve 21 which may be clamped in position by a set screw 22, and such sleeve has a bracket 23 extending rearwardly therefrom to which is pivoted by a bolt 24 the bobbin tip supporting arm 25. The bobbin tip supporting arm 25 in accordance with the present invention is normally under the influence of yielding means to maintain it in its upper or normal position, and in the present instance of the invention a spring 26 is mounted upon the pivotal support 24, and one end of the spring is connected at 27 to the bobbin tip supporting arm 25, and the other end 28 is engaged beneath a fixed pin 29 extending from the sleeve 21, the construction being such that the spring 26 acts to maintain the bobbin tip supporting arm 25 in its upper or raised position, as indicated in Fig. 4, with permissive movement, nevertheless, about its pivotal support 24 in a downward direction during the action of the transfer, as will more fully appear. To limit the upward swinging movement of the arm 25 under the action of the spring 26, a stop 30 may be employed, as indicated in Fig. 4.

The rear end portion of the bobbin tip supporting arm 25 has pivotally connected thereto at 31 the bobbin tip support 32. Preferably the rear end portion of the pivotal arm 25 is bifurcated, as indicated at 33, and between the walls of the bifurcation the bobbin tip support 32 is pivoted.

In accordance with the present invention, the bobbin tip support 32 (as fully shown in Fig. 5) has the downwardly extending tip supporting arm 34 formed with a rearwardly turned curved portion which is normally out of the path of movement of the bobbin tip when the bobbin is in transferring position. Such normal position of the bobbin tip support 32 as indicated in Figs. 1 and 4, may be variously contrived, but in the present instance of the invention, the bobbin tip support 32 is overweighted at its lower end with the result that the curved bobbin-engaging portion 34 will normally hang to one side of the path of movement of the bobbin tip next to the transfer. The full line position in Fig. 5 well illustrates this inoperative position of the bobbin tip support 32, while the dotted line

position in Fig. 5 shows the bobbin tip support in the position it occupies when it is in operative position below the feeler tip, as will more fully appear.

The pivotal bobbin support has the upwardly extending tail portion 35, which may be curved, as indicated in Figs. 4 and 5, and is so disposed with respect to the tip pusher arm 19 that during normal weaving operation the arm 19 is not engaged with the tail portion 35 of the bobbin tip support. When, however, the transfer moves downwardly in effecting transfer of a filling carrier to the shuttle, the tip pusher arm 19 engages the inclined or curved surface of the tail 35, and when the tip of the filling carrier has been engaged by the bifurcated end portion 36 of the tip pusher, the latter will engage the tail portion 35 and perforce swing the bobbin tip support 32 from its full to its dotted line position, Fig. 5, wherein the portion 34 of the bobbin tip support takes position under the bobbin tip and holds the latter in the bifurcation or crotch 36 of the tip pusher. The tip of the bobbin during transfer is therefore received in the crotch or bifurcation 36 of the tip pusher arm, and after such engagement the tip pusher arm 19 contacts with the upwardly extending tail 35 of the tip pusher and swings it from its normal inoperative position to its operative position under the tip of the bobbin to be transferred. This relation of parts is indicated in Fig. 2 and it will be noted that the tip of the bobbin is held in the notch or bifurcation of the tip pusher, and below the tip of the bobbin is the portion 34 of the bobbin tip support. In the position indicated in Fig. 2 where the bobbin has not yet been moved from the hopper under the downward action of the transfer, it will be noted that the bobbin tip supporting arm 25 has not yet been turned about its pivotal support 24 but that the bobbin tip support 32 has been moved by the tip pusher arm 19 to carry the end portion 34 of the bobbin tip support into operative position below the bobbin tip. Upon further downward movement of the transfer, as indicated in Fig. 3, the tip pusher arm acting through the tail portion of the bobbin tip support 32 will cause the bobbin tip supporting arm 25 to turn downwardly about its pivotal support 24 and permit the bobbin tip support to enter the shuttle in a position best calculated to properly position the tip portion of the bobbin in the bobbin chamber of the shuttle. As the transfer moves upwardly after having effected the transfer, the bobbin tip supporting arm 25 will rise, and since the pressure of the tip pusher arm has been removed from the tail 35 by upward movement of the transfer, the bobbin tip support 32 will move from its

operative position below the bobbin tip to its normal or inoperative position which it will fully reach when the transferrer and the bobbin tip supporting arm have completed their upward movements.

Inasmuch as the bobbin tip support 32 is to be swung from its inoperative to its operative position beneath the bobbin tip by the tip pusher arm 19 during the action of the 10 transferrer, and since such action by the tip pusher arm is to effect downward movement of the bobbin tip supporting arm 25, it is desirable in most instances to provide a bobbin tip support 32 with stops to limit its 15 swinging movements. These stops in the present instance of the invention are formed by slabbed-off portions 37 and 38 of the bobbin tip support. Normally the bobbin tip support 32, as indicated in Fig. 5, will hang 20 in its inoperative or full line position under the action of gravity, since the lower arm of the bobbin tip support is heavier than the upper one or is over-weighted, and during such normal position the slabbed-off portion 38 will rest upon the front wall 25 of the bifurcation 33 of the supporting arm. When, however, during transfer, the tip pusher arm 19 engages the tail 35, the bobbin tip support will be turned upon its 30 pivotal mounting 31 from its full to its dotted line position, Fig. 5, thereby carrying the end 34 into position below the bobbin tip, and at such time the slabbed-off portion 37 will engage the front wall of the bifurcation 33, as indicated by dotted lines 35 in Fig. 5, and thereby limit the swinging movement of the bobbin tip support from its inoperative to its operative position. When the stop 37 rests against the front 40 wall of the bifurcation, the downward push of the tip pusher arm 19 has no effect in further turning the bobbin tip support but the downward push acts through the tail 35 to effect downward movement of the supporting arm 25 without placing the strain directly on the bobbin tip.

What is claimed is:—

1. In a filling replenishing loom, the combination of the transferrer having a bobbin tip pusher, a pivotally mounted bobbin tip supporting arm, a spring normally acting to raise the arm to normal position, a bobbin tip support pivotally mounted on the supporting arm and having an upwardly extending tail adapted to be engaged by the tip pusher on replenishment of filling to swing the tip support under the bobbin and by continued movement of the transferrer to turn the bobbin tip supporting arm upon its pivot.

2. In a filling replenishing loom, the combination of the transferrer having a bobbin tip pusher, a pivotally mounted bobbin tip supporting arm, a spring normally acting to raise the arm to normal position, a bob-

bin tip support pivotally mounted on the supporting arm and having an upwardly extending tail adapted to be engaged by the tip pusher on replenishment of filling to swing the tip support under the bobbin and 70 by continued movement of the transferrer to turn the bobbin tip supporting arm upon its pivot, and stops for limiting the swinging movement of the bobbin tip support under the stress of the tip pusher. 75

3. In a filling replenishing loom, the combination of the transferrer, a tip pusher arm extending therefrom and having a tip pusher, a bobbin tip supporting arm pivotally mounted to swing downwardly during transfer, a bobbin tip support pivotally mounted on said arm and normally occupying an inoperative position relative to the bobbin tip, a tail extending upwardly from the bobbin tip support and normally in 80 position to be engaged by the tip pusher arm during transfer to first cause the bobbin tip support to be extended beneath the bobbin tip and then to turn the bobbin tip supporting arm about its pivotal support. 85

4. In a filling replenishing loom, the combination of the transferrer, a tip pusher arm extending therefrom and having a tip pusher, a bobbin tip supporting arm pivotally mounted to swing downwardly during transfer, a bobbin tip support pivotally mounted on said arm and normally occupying an inoperative position relative to the bobbin tip, a tail extending upwardly from the bobbin tip support and normally in 90 position to be engaged by the tip pusher arm during transfer to first cause the bobbin tip support to be extended beneath the bobbin tip and then to turn the bobbin tip supporting arm about its pivotal support. 95

5. In a filling replenishing loom, the combination of the transferrer having a bobbin tip pusher, a pivotally mounted bobbin tip supporting arm adapted to swing downwardly during transfer and having a bobbin tip support loosely pivoted thereon to normally occupy an inoperative position out of the path of the bobbin tip and provided with an upwardly extending tail adapted to be struck by the bobbin tip pusher during transfer to first move the lower end of the bobbin tip support to a position beneath the bobbin tip and then effect downward pivotal movement of the bobbin tip supporting arm. 110

6. In a filling replenishing loom, the combination of the transferrer, a support secured to the loom frame, a bracket secured to said support opposite the bobbin tip, a bobbin tip supporting arm pivotally mounted upon the bracket to swing downwardly on transfer, a bobbin tip support pivotally mounted upon the bobbin tip supporting arm, a 125 130

spring normally acting to hold the bobbin tip supporting arm yieldingly in its normal raised position, and means acting during transfer to move the bobbin tip support into position beneath and into engagement with the bobbin tip and then by further movement of the transerrer to move the bobbin tip supporting arm downwardly.

7. In a filling replenishing loom, the combination of the transerrer, a support secured to the loom frame, a bracket secured to said support, a bobbin tip supporting arm pivotally mounted upon the bracket, a bobbin tip support pivotally mounted upon the bobbin tip supporting arm, a spring normally acting to hold the bobbin tip supporting arm yieldingly in its normal position, means acting during transfer to move the bobbin tip support into position below the bobbin tip and then to move the bobbin tip supporting arm downwardly, and a stop to limit the upward movement of the bobbin tip supporting arm.

8. In a filling replenishing loom, the combination of the transerrer, a support secured to the loom frame, a bracket secured to said support, a bobbin tip supporting arm pivotally mounted upon the bracket, a

bobbin tip support pivotally mounted upon the bobbin tip supporting arm and weighted to normally maintain the bobbin tip support out of the path of the bobbin tip, a spring normally acting to hold the bobbin tip supporting arm yieldingly in its normal position, and means acting during transfer to move the bobbin tip support into position below the bobbin tip and then to move the bobbin tip supporting arm downwardly.

9. In a filling replenishing loom, the combination of the transerrer, a support secured to the loom frame, a bracket secured to said support, a bobbin tip supporting arm pivotally mounted upon the bracket, a bobbin tip support pivotally mounted upon the bobbin tip supporting arm, a spring normally acting to hold the bobbin tip supporting arm yieldingly in its normal position, means acting during transfer to move the bobbin tip support into position below the bobbin tip and then to move the bobbin tip supporting arm downwardly, and stops to limit the swinging movements of the bobbin tip support on the arm.

In testimony whereof, I have signed my name to this specification.

ISAAC SNOW.
